UNITED STATES PATENT OFFICE.

MAX MICHALK, OF MONTREAL, QUEBEC, CANADA.

UNIVERSAL BABBITTING EQUIPMENT.

Application filed August 8, 1925. Serial No. 49,081.

To all whom it may concern:

Be it known that I, MAX MICHALK, a subject of the King of Great Britain, residing at Montreal, Province of Quebec, Canada, **5** have invented certain new and useful Improvements in Universal Babbittting Equipment; and I do hereby declare that the following is a full, clear, and exact description of the invention, such as will enable others **10** skilled in the art to which it appertains to make and use the same.

The present invention pertains to a novel universal babbittting equipment designed for casting babbitt linings on bearings.

15 The principal object of the invention is the provision of a device of this character which is constructed to prevent accidents such as occur very often in the use of wooden mandrels. In the accomplishment **20** of this object, the mandrel is constructed of metal, and the remaining parts constituting the mould are so arranged that leakage is impossible. Not only does the invention eliminate the use of wooden parts but it also **25** reduces the labor to a great extent.

A further feature of the invention is that the apparatus is adjustable to accommodate bearings of various angular magnitude and of a given radius of curvature. To this **30** end adjustable liner plates are attached to flanges extending from the edges of the mandrels and may be positioned at various points on the curved surface of the mandrel. The bearing to be lined is then clamped **35** against these plates whereby the mould for the molten bearing metal is completed.

Still another feature of the invention is the provision of a portable stove and hot plate for removing worn linings from bearings. This device comprises a curved plate supported beneath a small stove and adapted **40** to be run along the worn lining in order to melt and thus remove it.

The invention is fully disclosed in the following description and in the accompanying drawings in which;

Figure 1 is a perspective view of one of the mandrels;

Figure 2 is another perspective view **50** thereof taken from the rear side;

Figure 3 is a plan view thereof;

Figure 4 is a perspective view of one of

the base plates, showing the bottom thereof;

Figure 5 is a bottom plan view of a pair of base plates joined together; **55**

Figure 6 is a perspective view of a unit employed for small sizes;

Figure 7 is a plan view of the form shown in Figure 1 in operative position with a bearing clamped thereto; **60**

Figure 8 is a section on the line 8—8 of Figure 7;

Figure 9 is a perspective view of the clamp plate or liner shown in Figure 7;

Figure 10 is a plan view of the assembly **65** for lining a shorter bearing;

Figure 11 is a side elevation corresponding to Figure 10;

Figure 12 is a perspective view of one of the liner plates used in Figure 11; **70**

Figure 13 is a perspective view of an assembly for very short bearings;

Figure 14 is a perspective view of one of the liner plates used in Figure 13;

Figure 15 is a perspective view of an **75** assembly for molding eccentric straps;

Figure 16 is a perspective view of a mandrel section for a small size of lining;

Figure 17 is a perspective view of the counterpart of the section shown in Figure 16; **80**

Figure 18 is an inner side elevation of a plurality of superposed sections for use in connection with a wide bearing; and

Figure 19 is a section on the line 19—19 **85** of Figure 18.

Reference to these views will now be made by use of like characters which are employed to designate corresponding parts throughout. **90**

The embodiment shown in Figure 1 and associated views is designed for casting babbitt linings of 3 $\frac{3}{8}$ -inches to 6 $\frac{3}{8}$ -inches in diameter. The assembly includes a semi-cylindrical mandrel 1 mounted on a base **95**

plate 2. The bottom edge of the mandrel is formed with a diametrical rib 3 from which extends a perpendicular slotted arm 4 radially to the curved wall. The lower surface of the bottom plate has a flange **100**

5 from the midpoint in which extend a pair of arms 6 to the opposite corners and an arm 7 to the midpoint of the opposite side. The flange 5 has a pair of alined spaced

slots 8, and the intersection 9 of the arms 6 and 7 is formed with a slot 10. A bolt and nut device 11 passed through the slotted arm 4 and into the slot 10 holds the mandrel 1 and base plate together. The edges of the mandrel 1 have inwardly extending flanges 12 to which are secured a pair of back plates 13 by means of bolts and nuts 14. The lower edges of the plates have slots 15 through which are passed bolts 16 extending into the slots 8 whereby the back plates are further secured to the base plate.

In the use of this form of device, the bearing 17 to be lined is based upon the base plate 10 so that a space corresponding to the thickness of the desired lining is retained between the mandrel and the bearing. In this position the flanges 18 of the bearing engage the back plates 13 as illustrated in Figure 7. A liner or clamp plate 19 is now placed over the bearing so that the flanges 20 of the clamp plate engage the flanges 18 of the bearing. Clamps 21 are now applied to engage the flanges 20 and back plates 13, whereby the bearing is secured in proper position. The Babbitt metal 22 is now poured into the space between the mandrel and the bearing, and allowed to harden before the mould is dismantled. The liner 19 is formed with a vertical slot 23 to accommodate the rib 17' on the back of the bearing if the bearing has such a rib.

In casting linings of the same radius of curvature as that for which the described embodiment is adapted, but of less angular magnitude, the assembly shown in Figure 10 is employed. The bearing flanges 18' are necessarily spaced from the back plates 13, and in order to maintain this spacing, supplemental liner plates 24 are placed against the inner faces of the flanges and also against the outer wall of the mandrel to close the casting space. The plates 24 carry screws 25 which project through appropriate apertures 26 in the back plates 13. The plates 24 are held at the proper distance from the plates 13 by means of clamp nuts 27 threaded on the screws and bearing against the plates 13. Clamps 28 are applied over the plates 24 and flanges 20' of the liner 19' in order to retain the bearing 17'. The metal is poured into the spaces defined by the mandrel, bearing and plates 24 in the manner already mentioned, and the assembly is dismantled after the metal has hardened.

A modified form of apparatus for casting linings of still smaller angular magnitude but of the same radius of curvature is shown in Figure 13. In this construction, the liner plates 30 for defining the straight edges of the babbitt lining are adapted for connection to the back plates 13 by means of slotted fingers 31. Screws 32 are passed through the apertures 26 and through the

slotted fingers 31, and are clamped to these members by means of nuts 33 to hold the parts in proper spacing. To the liner plates 30 are secured angle irons 34 which are so spaced as to suitably retain the bearing to be lined.

In order to cast eccentric straps, a pair of base plates 2 are connected by means of bolts 35 passed through the slots 8 of two engaging flanges 5 and locked therein as shown in Figure 5. On the upper base of the joined plates is placed a pair of semi-circular bearing yokes 36 fastened together by bolts 37. A cylindrical drum which may consist of a pair of similar sections 38 is placed within the confines of the yokes in eccentric relation. The metal is now poured into the space between the drum and the yokes, whereby the lining is formed eccentric to the yokes.

The unit employed for bearings of a diameter from $\frac{7}{8}$ -inch to 3-inches is illustrated in Figure 6. This unit comprises a plane base plate 39 having a central aperture 40, together with a solid cylindrical drum 41 with a spindle 42 adapted to enter the aperture. After the drum has been placed upon the plate 39, it is surrounded by the bearing, and the metal is poured into the space between the drum and bearing in the usual manner.

The embodiment shown in Figures 16 and 17 is designed for lining the bearings of $\frac{7}{8}$ -inch to $2\frac{7}{8}$ -inches in diameter. This form comprises a pair of semi-cylindrical drum sections 43 and 44 having diametrical arms 45 and 46 respectively across their edges. Each arm 45 on the section 43 has a keyhole slot 47, and the corresponding arms 46 on the other section 44, each have an aperture 48.

The parts are fastened together by bolts positioned in the apertures 48 and slidably inserted into the inner portions of the slots 47. The sections also have intermediate arms 49 which may be connected by suitable fastening devices passed through apertures 50, if the sections are open at one end.

In order to cast wide bearings, a plurality of mandrels 1 are superposed in the manner illustrated in Figures 18 and 19. For this purpose, the upper edge of each mandrel has a plurality of ears 51, and the back plates 13 have similar ears 52 at their upper edges. The members are so arranged that ears engage ears and ribs 3 engage similar members on the adjacent sections. These parts are then bolted together as clearly shown in Figures 18 and 19. The remainder of the process is carried out in the manner already described.

While a specific embodiment of the invention has been illustrated and described, it is to be understood that various alterations in the details of construction may be made

without departing from the spirit of the invention as indicated by the appended claims.

Having thus fully described the invention, what I claim as new and desire to protect by Letters Patent is:

- 5 1. Babbetting equipment comprising a curved mandrel, and liner plates adjustably connected to said mandrel.
- 10 2. Babbetting equipment comprising a curved mandrel, back plates extending outwardly from the edges of said mandrel, and liner plates adjustably attached to said back plates.
- 15 3. Babbetting equipment comprising a curved mandrel, back plates extending outwardly from the edges of said mandrel, liner plates adjustably attached to said back plates, and means for interlocking a plurality of said mandrels in superposed position.

4. Babbetting equipment comprising a curved mandrel, liner plates adjustably connected to said mandrel, and angle irons adapted for attachment to said line plates.

5. Babbetting equipment comprising a 25 curved mandrel, back plates extending outwardly from the edges of said mandrel, liner plates adjustably attached to said back plates, and angle irons adapted for attachment to said liner plates.

6. Babbetting equipment comprising a curved mandrel, back plates extending outwardly from the edges of said mandrel, screws adjustably mounted in said back plates, and liner plates carried by said 35 screws.

In witness whereof I have hereunto set my hand.

MAX MICHALK.
